CLARIFICATION OF BLACK FOUNDRY WASTE WATERS

Robert B. Booth and John M. Dobson, Stamford, Conn., assignors to American Cyanamid Company, New York, N. Y., a corporation of Maine

Application March 11, 1952, Serial No. 275,994

11 Claims. (Cl. 22—217)

This invention relates to the clarification of foundry waste effluents.

A serious waste disposal problem in foundry practice arises in disposing of the inky-black waters originating from foundry dust collectors, wet methods and such various operations as cleaning of foundry sands, sand blasting and hydraulic cleaning of castings, etc. We have now discovered a means of continuously removing the contaminants from such foundry waters as a low bulk concentrate and if desired, recirculating the clarified water that has been freed of impurities; thus, our invention largely eliminates waste disposal and stream pollution problems that have plagued the industry heretofore and effects a great economy in the expenditure of water.

American steel foundry practice in the manufacture of green sand castings consists of milling or mulling bentonite or clay with a farinaceous binder, such as corn flour, in a mill, and mixing it with water and sand to obtain the consistency necessary for moldability. This sand becomes facing sand and is placed next to the pattern. After removal of the pattern, the metal in the casting comes in contact with this facing sand and reproduces the design of the pattern or model. This practice is used on castings from one to five thousand pounds each in weight, but is generally conceded to be unsuitable for castings in excess of this weight, which are usually made in oven dried molds, since the green sand will not maintain its strength long enough to fill the mold cavity for very heavy castings. After the castings have been shaken out of the sand, the entire contents of the flask or molding box may go through a sand reclamation system designed to remove steel or metal particles with a magnetic separator. The sand then goes through a series of screens, removing many of the fines, in order to maintain suitable permeability for the elimination of gasses in pouring.

The reclaimed product is then called heap sand or backing sand, and is used to back up the all new sand facing next to the pattern. The heap or backing sand, is not suitable for reuse as a facing sand, because it has become contaminated with various ingredients which have become burnt and inert, such as clay and corn flour. In addition, certain molds are coated with linseed oil or its equivalent. This oil coating having been burned onto the sand, is very difficult to remove by washing, scrubbing or ignition.

Heap sands may be cleaned by scrubbing or washing, followed by screening, classification, settling, etc. Such cleaning processes produce the above-mentioned black foundry waters. These waters contain burned sand particles, that is, carbon-coated silica, as well as other constituents of the mixtures used for the molds, for example, clay, bentonite, carbon, graphite, thermosetting resins, high organic polymers, and thermal degradation products of the organic binders used, in a highly colloidal form. Clarification by settling and/or filtration is extremely difficult and is not commonly used because of the inefficiency of such methods. Reagents which are known to be effective in promoting the flotation of carbon and graphite, for

example, fuel oil in combination with frothers, surprisingly enough, do not promote the flotation of this colloidal black matter.

In recent years American foundries have adopted sand blasting to clean both the casting itself and to scrub off the pyrolyzed coatings from the foundry sand. Dry sand blasting is sometimes used, the sand entrained by the out-going air being trapped in water to give suspensions which must be clarified before disposal. Wet sand blasting is highly effective; a mixture of sand and water under high pressure (e. g., up to 1800 lb./sq. inch) is directed against the casting to remove any adhering sand, decomposition products, oxidation products, etc., from the casting and simultaneously to clean the sand itself. The cleaned sand is recovered for reuse and the water after the separation is heavily loaded with the above-described solids. A portion of these solids may be removed by settling, but large quantities of the solids, particularly the fines and colloidal fractions, remain in suspension and create a serious disposal problem.

High pressure water alone may be used for the cleaning of castings. As described above, high pressure streams or sprays of water are directed against the casting to dislodge and remove adhering sand, scale, decomposition products, etc. This operation also produces dark-colored suspensions which are extremely difficult to filter and clarify and which create the same problems in reuse and disposal as indicated above.

It is, therefore, an object of the present invention to provide both an apparatus for, and a method adapted to, carry out the foundry sand cleaning operation and at the same time to remove carbonaceous impurities from the foundry waste water in an efficient but simple manner.

Dark-colored suspensions also result when wet dust collectors are used in foundry practice; such suspensions present the same disposal problem as described above.

It is an advantage of our new process that the suspended solids are removed from these contaminated waters to produce a clarified effluent containing less than 500 p. p. m. solids. In this manner, we have eliminated most of the undue wear of the high pressure circulating pumps that normally handle contaminated foundry waters. Thus, if desired, it is now possible to use a "locked system" in which the clarified waters are recirculated and the contaminants are continuously removed as a low bulk flotation concentrate. On the other hand, the clarified waters are sufficiently free of solids to allow their disposal in streams without presenting a serious pollution problem.

In our new process these foundry waste waters are clarified by flotation with anionic collectors, either in the presence or absence of glue and related substances, or the waters may be first settled with or without settling agents in combination with the flotation step mentioned above. The choice of the method used depends on the type of waste water to be treated and our invention will be illustrated in conjunction with the accompanying drawings in which Figure 1 is a flow sheet of a continuous method of recovering sand sufficiently clean for reuse and water suitable for circulating. Figure 2 illustrates an adaptation of our process which permits the clarified water to be reused in the wet type dust collector. Figure 3 is a flow sheet of a continuous process for cleaning castings by wet sand blasting and recovering the sand so used in a form sufficiently clean for reuse, providing for continuous clarification and circulation of the water. Figure 4 is a flow sheet which illustrates a method of cleaning castings hydraulically with high pressure water, separation of the sand from the black water and subsequent cleaning of the sand to obtain cleaned sand suitable for reuse; this circuit permits removing those impurities suspended in the effluent waters from the cleaning room and sand scrubber.

A variety of settling agents including lime, alum, iron

closed herein but is to be accorded the full scope of the claims so as to embrace any and all equivalent devices.

Having described our invention, what we claim as new and desire to secure by Letters Patent is:

1. A mechanical action for artificial limb joints comprising a relatively stationary member and a ratchet segment rotatably mounted on the member, a lever rotatably mounted on the member with the rotational axis adjacent to the circumference of the ratchet segment, a locking bar on said lever having opposite curved faces positioned generally perpendicular to the radius from the rotational axis of the lever, said segment having a series of spaced generally radially extending bar receiving notches with faces complementary to the respective faces of the bar when in bar receiving position, said rotational axis of the lever being at a point adjacent a line tangent to an arc about the axis of said segment struck through the centers of the faces of said notch.

2. A mechanical action for artificial limb joints comprising a relatively stationary member and a ratchet segment rotatably mounted on the member on the axis of rotation of the joint, a lever rotatably mounted on the member with the rotational axis adjacent to and exterior of the circumference of the ratchet segment, a locking bar on said lever having opposite faces positioned generally perpendicular to the radius from the rotational axis of the lever and the faces, said segment being subject to a rotative load and having a series of spaced generally radially extending bar receiving notches with faces complementary to the respective faces of the bar when in bar receiving position, said rotational axis of the lever being within an angular distance of a line tangent to an arc about the axis of said segment struck through the centers of the faces of said notch such that the component of the force resulting from application of a rotative load tending to disengage the bar from the notch is less than the frictional force on the respective contacting faces.

3. A mechanical action for artificial limb joints comprising a relatively stationary member and a ratchet segment rotatably mounted on the member on the axis of rotation of the joint, a lever rotatably mounted on the member with the rotational axis adjacent to and exterior of the circumference of the ratchet segment, a locking bar on said lever having opposite arcuate faces positioned generally perpendicular to the radius from the rotational axis of the lever and the faces, said segment having a series of spaced generally radially extending bar receiving notches with arcuate faces complementary to the respective faces of the bar when at bar receiving position, said rotational axis of the lever being within an angular distance of five degrees inside of a line tangent to an arc about the axis of said segment struck through the centers of the faces of said notch.

4. A mechanical action for artificial limb joints comprising a relatively stationary member and a ratchet segment rotatably mounted on the member on the axis of rotation of the joint, a lever rotatably mounted on the member with the rotational axis adjacent to and exterior of the circumference of the ratchet segment, a locking bar on said lever having opposite arcuate faces of radius of curvature determined by the distance between the rotational axis of the lever and the respective face, said segment having a series of spaced generally radially extend-

ing bar receiving notches with arcuate faces complementary to the respective faces of the bar, said rotational axis of the lever being at a point within an angular distance of 15 degrees on either side of a line tangent to an arc centered at the axis of said segment and through the centers of the faces of a notch in bar engaging position, the faces of said notches having positions wherein said last faces are in engagement substantially throughout their areas with the respective faces of the bar when in bar engaging position.

5. A mechanical action for artificial limb joints comprising a pair of members wherein one member is adapted for attachment to a natural limb, parallel plates on one of the members, the other of said members comprising a tubular sleeve rotatably mounted on said plates providing thereby an articulating joint for said action, a ratchet segment fixed on said sleeve having a series of spaced generally radially extending notches, a lever pivotally mounted at a center of rotation on said one member, a locking bar fixed transversely on the lever, and an alternator connected between the lever and one of said members adapted to releasably hold said bar out of notch engagement position, said bar having opposite notch contacting faces curved in the same general direction and said notches having opposite curved bar engaging faces complementary to and adapted to engage the respective faces of the bar when in bar engaging position.

6. A mechanical action for artificial limb joints comprising a relatively stationary member adapted for attachment to a natural limb, parallel plates on said member and a tubular sleeve rotatably mounted on said plates providing thereby an articulating joint for said action, a ratchet segment fixed on said sleeve having a series of spaced generally radially extending notches, a lever pivotally mounted at a center of rotation on said member, a locking bar fixed transversely on the lever, a spring on said member normally urging said bar toward a notch engagement position, and an alternator connected between said member and the lever adapted to releasably hold said bar out of notch engagement position, said bar having opposite notch contacting faces of arcuate form and of radius determined by the distance between the respective face and said center of rotation of the lever, said notches having opposite bar engaging faces of arcuate form complementary to and adapted to engage the respective faces of the bar when in bar engaging position.

7. A ratchet resistant mechanical action for artificial limb joints comprising a base, a ratchet segment rotatably mounted on the base and a locking bar having a pivotal mounting on said base, said locking bar having opposite segment-engaging faces curved in the same general direction about the axis of said pivotal mounting, said segment having a series of peripheral bar receiving notches with opposite faces respectively complementary to the faces on said bar.

EXAMPLE 5

Samples of black-colored waters from a casting cleaning operation in a Pennsylvania cast iron foundry containing about 2100 p. p. m. suspended solids were settled five minutes with lime and floated one minute with black liquor soap or black liquor soap in combination with pine oil as frother. The lime was added as milk of lime or in dry form. Removal of suspended solids was as follows:

Table IV

Run A	Run B
0.60 lb./1,000 gals. lime as milk of lime.	0.2 lb./1,000 gals. dry lime.
0.11 lb./1,000 gals. black liquor soap.	0.22 lb./1,000 gals. black liquor soap.
0.07 lb./1,000 gals. pine oil.	No pine oil used.
94.6% removal of suspended solids.	91.3% removal of suspended solids.

EXAMPLE 6

Samples of black-colored waters from a Pennsylvania cast iron foundry were treated by flotation. The waters, containing 4230 p. p. m. suspended solids, were passed continuously to a settling tank, treated with 0.23 lb./1000 gallons of lime and allowed to settle seven minutes. The waters were then passed to a Fagergren flotation machine, treated with 0.44 lb./1000 gallons black liquor soap and 0.05 lb./1000 gallons bone glue, and floated for four minutes. An effluent containing 390 p. p. m. suspended solids was produced.

A second sample of sand blast waters from this foundry was also treated. From a water containing 2720 p. p. m. suspended solids, an effluent containing 230 p. p. m. was produced by the above-outlined procedure, employing per 1000 gallons 0.7 lb. hydrated lime, 0.44 lb. black liquor soap, and 0.05 lb. bone glue. The flotation concentrate was black in color when wet and gray-to-black on drying at 110° C. The dried solids were ignited at about 1000° C. to remove volatile constituents; the resulting residue, 71.2% of the sample, was light yellow in color and was composed mainly of silica with some silicate minerals and iron oxides also present.

EXAMPLE 7

A foundry sand contaminated by use in steel casting was scrubbed and washed with water. The sand, after this cleaning operation, was recovered by classification and settling and the resulting wash waters were reserved for flotation testing. These waters, black in color, were typical of the effluents produced in foundry sand reclamation and contained 3050 p. p. m. suspended solids.

The coarser portions of these contaminants settled out on standing, but the finer portions remained in suspension for several days; in fact, at the end of seven days the supernatant liquid was still highly colored with suspended colloidal material.

In conducting tests on these waters, representative portions were settled for two and one-half minutes with a settling agent to remove a portion of the suspended solids and the supernatant liquid, still contaminated with suspended matter, was passed to a Fagergren flotation machine, treated with flotation reagents, and floated for one and one-half minutes. The suspended solids, thus concentrated in the froth, were skimmed off.

Since the waters were contaminated with carbonaceous materials, charred and carbon-coated sand grains and mineral matter, etc., an attempt was made to clarify the waters by settling, followed by flotation reagents usually employed for floating carbon, graphitic material, etc., in regular flotation practice.

The waters were first settled with 0.54 lb./1000 gallons alum for five minutes and the supernatant liquid floated for one and one-half minutes with 0.15 lb./1000 gallons of a higher alcohol frother. No promotion of the suspended solids was obtained. Similarly, a combination of

6

0.15 lb./1000 gallons alcohol frother and 0.15 lb./1000 gallons fuel oil #2 did not promote the flotation of the suspended solids. Pine oil, 0.05 lb./1000 gallons, gave good froth, but did not promote the flotation of the suspended solids. Thus, reagents commonly used in flotation of carbon, graphite, etc., were not effective for removing the carbon-contaminated solids from these waters. Black liquor soap, 0.44 lb./1000 gallons, gave an effluent containing 700 p. p. m. suspended solids, a considerable improvement over the above-listed results. Glue, 0.07 lb./1000 gallons, produced some froth, but very little collection of the suspended solids; a combination of 0.7 lb./1000 gallons glue and 0.07 lb./1000 pine oil also gave poor promotion of the suspended solids, resulting in an effluent containing about 2500 p. p. m. suspended solids. However, a marked improvement in clarity was obtained using 0.10 lb./1000 gallons black liquor soap in combination with 0.036 lb./1000 glue; the froth and promotion of solids was improved markedly and the resulting effluent contained 625 p. p. m. suspended solids, considerably less than obtained in any of the tests described above.

In view of the improved results obtained with the glue-black liquor soap combination, a number of settling-flotation tests were conducted, employing a variety of glues and related materials and several anionic type flotation collectors. The above-described waters were settled three minutes with various settling agents, as described above, and then floated one and one-half minutes with various glues and related products used in combination with a variety of anionic type flotation promoters. The glue and promoters were added in two equal stages, the first at the start, followed by a 15-second conditioning period, and the second after one-half minute of flotation. The following table summarizes the results obtained in these tests.

Table V

¹ Figures in parentheses are jellygrams.

After settling with 0.54 lb./1000 gallons alum, 0.07 lb./1000 gallons of gelatine (acid and basic types) were used in separate tests with 0.44 lb./1000 gallons black liquor soap; effluents containing 110 and 126 p. p. m., respectively, were produced. After a similar settling treatment, two ammoniated caseins were used in amounts of 0.07 lb./1000 gallons in combination with 0.44 lb./1000 gallons black liquor soap; the resulting effluents contained 350-400 p. p. m. suspended solids.

In another series of tests on this water, 0.25 lb./1000

flotation in the presence of black liquor soap and in the absence of an added reagent capable of activating silica, to produce a flotation concentrate rich in said impurities and a water tailing substantially free thereof; and recycling at least a portion of said tailing for reuse.

6. In a method of foundry operation which comprises casting metal in a sand mold, whereby the organic binder present in said mold is pyrolyzed and carbonized; freeing the carbonized organic matter, finely divided silica and other impurities from said sand by a hydraulic process, whereby a suspension of said impurities in water is obtained; the steps which comprise settling said water suspension; subjecting the settled water suspension to froth flotation in the presence of saponified talloel and a small amount of glue and in the absence of an added reagent capable of activating silica, to produce a flotation concentrate rich in said impurities and a water tailing substantially free thereof; and recycling at least a portion of said tailing for reuse.

7. In a method of foundry operation which comprises casting metal in a sand mold, whereby the organic binder present in said mold is pyrolyzed and carbonized; freeing the carbonized organic matter, finely divided silica and other impurities from said sand by a hydraulic process, whereby a suspension of said impurities in water is obtained; the steps which comprise settling said water suspension; subjecting the settled water suspension to froth flotation in the presence of talloel and a small amount of glue and in the absence of an added reagent capable of activating silica, to produce a flotation concentrate rich in said impurities and a water tailing substantially free thereof; and recycling at least a portion of said tailing for reuse.

8. In a method of foundry operation which comprises casting metal in a sand mold, whereby the organic binder present in said mold is pyrolyzed and carbonized; freeing the carbonized organic matter, finely divided silica and other impurities from said sand by a hydraulic process; the steps which comprise settling said water suspension; subjecting the settled water suspension to froth flotation in the presence of black liquor soap and a small amount of glue and in the absence of an added reagent capable of activating silica, to produce a flotation concentrate rich in said impurities and a water tailing substantially free thereof; and recycling at least a portion of said tailing for reuse.

9. In a method of foundry operation which comprises casting metal in a sand mold, whereby the organic binder present in said mold is pyrolyzed and carbonized; freeing the carbonized organic matter, finely divided silica and other impurities from said sand by a hydraulic process, whereby a suspension of said impurities in water is obtained; the steps which comprise settling said water suspension; subjecting the settled water suspension to froth flotation in the presence of saponified talloel and a small amount of glue and in the absence of an added reagent capable of activating silica, to produce a flotation concentrate rich in said impurities and a water tailing substantially free thereof; and recycling at least a portion of said tailing for reuse.

10. A method according to claim 1 in which the settling step is carried out in the presence of alum.

11. A method according to claim 1 in which the settling step is carried out in the presence of lime.
